HAT

Mildred M. Tapley, Wellesley Hills, Mass.

Application April 15, 1952, Serial No. 19,324

Term of patent 7 years

(Cl. D3—13)

To all whom it may concern:

Be it known that I, Mildred M. Tapley, a citizen of the United States, and residing at Wellesley Hills, in the county of Norfolk, Commonwealth of Massachusetts, have invented a new, original, and ornamental Design for a Hat, of which the following is the specification, reference being made to the accompanying drawing, forming a part thereof.

Fig. 1 is a front perspective view of a hat showing my design,

Fig. 2 is a top plan view thereof; and

Fig. 3 is a cross sectional view taken on the line 3—3 of Fig. 2.

I claim:

The ornamental design for a hat, as shown.

MILDRED M. TAPLEY.
